DESIGN FOR A BRAIDED FABRIC OR ARTICLE OF SIMILAR NATURE

Ernest Hansmann, New Bedford, Mass., assignor to The Continental Elastic Corporation, New Bedford, Mass.

Application October 25, 1938, Serial No. 80,669

Term of patent 3½ years

To all whom it may concern:

Be it known that I, Ernest Hansmann, a citizen of Germany, and resident of New Bedford, county of Bristol, State of Massachusetts, have invented a new, original, and ornamental Design for a Braided Fabric or Article of Similar Nature, of which the following is a specification, reference being had to the accompanying drawing, forming a part thereof.

A thread-wrapped cord construction forming a braided fabric rectangular in shape, having ornamental surface indentations with the broad faces of the fabric presenting a four row herringbone appearance with the two inner rows of cords of one color both extending in one direction, and outer rows of a color and direction contrasting with the said inner rows, and with a contrasting color design also formed at the narrow edges of said fabric.

I claim:

The ornamental design for a braided fabric or article of similar nature, as shown and described.

ERNEST HANSMANN.
